UNITED STATES PATENT OFFICE.

HENRY F. CLARK, OF OAKMONT, PENNSYLVANIA, ASSIGNOR TO WINDOW GLASS MACHINE COMPANY, OF PITTSBURGH, PENNSYLVANIA, A CORPORATION OF NEW JERSEY.

BURNER FOR FURNACES.

Application filed April 9, 1921. Serial No. 459,993.

To all whom it may concern:

Be it known that I, HENRY F. CLARK, a citizen of the United States, residing at Oakmont, in the county of Allegheny and State of Pennsylvania, have invented a new and useful Improvement in Burners for Furnaces, of which the following is a full, clear, and exact description.

My invention relates to burners for furnaces, and is particularly useful with glass pot furnaces used in drawing glass, but it of course may be used with other heating devices. My burner is applicable to such devices when it is desired to use raw producer gas.

The object of my invention is a simple arrangement for use in burning raw producer gas, and such a device which will, by reason of the features hereinafter described, be kept clean notwithstanding the presence of considerable quantities of heavy hydrocarbons.

A further object of my invention is such a device which will thoroughly mix the gas and air so as to effect a complete combustion.

A still further object of my invention is to somewhat retard the flow of the mixed gas and air through a comparatively long mixing and partial combustion passage before the mixture is discharged into the heating chamber, for the purpose of securing a complete combustion in the heating chamber, thus avoiding the deposit of soot and other objectionable matter in the heating chamber or on the usual glass pot when the device is used in connection with glass drawing machinery.

These and other objects will be more fully appreciated as the device is described in detail, in connection with the accompanying drawings forming a part thereof, and in which:—

Figure 1 is a sectional elevation of the burner, shown in connection with a glass pot furnace;

Figure 2 is a plan view of the device shown in Figure 1;

Figure 3 is a section on the line III—III of Figure 1; and

Figure 4 is a section on the line IV—IV of Figure 1.

In Figure 1 I have shown a gas main 1 of any desired construction, supported by a frame structure 2. A gas port 3 is connect-

ed with the gas main 1 through an opening 4, which may be closed by the saucer valve 5, which is operated by a hand wheel 6 or other suitable means. A man-hole 7 is provided in the end of the port 3 for purposes well understood.

The port 3 is also provided with a vertical dust leg 8, which is closed at the lower end by a valve arrangement 9 of any suitable character.

The exit end of the port 3 is somewhat contracted by the refractory lining, as shown at 10. Across the end of the port 3 are placed two adjustable plates or slides 11 and 12, as best shown in Figure 4. These plates are held in place by the members 13 and 14 and may be adjusted to provide any desired size of opening 15 between the edges of said plates. From Figure 4 it will be noted that the opening 15 is rectangular in shape, thus providing for a wide, thin stream of gas which issues therefrom at considerable velocity, the gas in the port 3 being under pressure.

Adjacent the discharge end of the port 3 is placed a separate member 16. This member has a flared end 17 which has plates 18 and 19 arranged in the end thereof in the same manner as the plates 11 and 12 are arranged in the end of the gas port 3. The plates 18 and 19 are held by friction by means of the members 20 and 21, and may be adjusted to vary the amount of air which will be taken into the member 16, as will be later explained. It may be noted at this point that the space between the ends of the member 16 and the port 3 is open to the atmosphere.

The chamber inside the member 16 may be designated as a mixing and partial combustion chamber, because in this chamber the air and gas are mixed as they flow toward the pot furnace or heating chamber 22. The mixing and partial combustion chamber 23 gradually increases in cross section toward the pot furnace or heating chamber 22, and at the point where the chamber 23 enters the furnace the said passage is inclined downwardly, as shown at 24. This is for the purpose of directing the mixture toward the bottom of the furnace or heating chamber, and the combustion mixture is then given a swirling motion by coming in contact with the sloping side of the furnace,

and in that manner the gas and air are further mixed and a complete combustion takes place.

The furnace is supported by any desired foundation structure 25, and the member 16 is suspended by members 26 which are carried by the beams 27 and angle 28; and in like manner one end of the gas port 3 is carried by the members 29 supported by an angle 30 which rests on the beams 27. It will, of course, be understood that any suitable or desired arrangement may be provided for carrying these parts, and this supporting means forms no part of my invention.

In operation, the gas from the main 1 passes through the connection 4 into the port 3 freely, because the saucer valve 5 is normally in the position shown in Figure 1. Therefore, the pressure in the port 3 is the same as in the main 1. The heaviest hydrocarbons in the gas will be deposited in the dust leg or clean-out chamber 8, due to the eddy formed at the point immediately over the upper end of the leg 8. The gas will then issue in a wide, thin stream through the opening 15, and having an injector effect, will draw air in with it from the atmosphere through the opening between the plates on the end of the port 3 and those on the end of the member 16. By this injector effect, a highly combustible mixture is secured, which has considerable velocity as it is drawn in through the flared end 17 of the member 16. Additional velocity is given by reason of the natural upward draft produced by the arrangement shown, in which the end 17 of the member 16 is at a substantial distance below the bottom of the furnace 22. As this mixture travels toward the furnace, the chamber 23 gradually increasing in cross section, a slight decrease in velocity is caused, and therefore what might be termed a "lazy" flame results. During the passage of the mixture through the chamber 23, the air and gas are completely mixed and issue from the point 24 into the furnace, where the combustion is completed and a very intense flame results, thus avoiding the formation of any deleterious products either on the furnace bottom and walls or on the pot 31, which must be kept perfectly clean in order to avoid trouble in the glass drawing operation. The pot 31 is of the reversible type having a chamber in both sides thereof, one of which chambers is being melted out while the drawing operation is proceeding from the other, whereupon the pot is then reversed, and the first chamber filled with molten glass while the other chamber is being melted out.

It will also be noted that the furnace is larger than is ordinarily employed, which, in combination with the particular arrangement described, offers a greater combustion

chamber which aids materially in the completeness of the combustion of the mixture in the heating chamber.

My invention has the advantages that it is simple in construction; it readily burns raw producer gas without the formation of deleterious products in the heating chamber; it has a natural draft, and is therefore substantially automatic in operation; it needs little or no attention; and means are provided for readily cleaning from the structure the heavy hydrocarbons deposited before the mixture is ignited. Furthermore, a complete combustion is effected, which results in more efficiency and economy, both in the consumption of fuel and in the upkeep or care which would otherwise be necessary.

I claim:

1. A producer gas combustion apparatus for glass furnaces or the like, comprising a relatively large heating chamber, a mixing and combustion chamber communicating therewith, said last chamber gradually increasing in cross section towards said heating chamber, and air and producer gas feeding means communicating with said mixing chamber at a distance from said heating chamber, substantially as described.

2. A producer gas combustion apparatus for glass furnaces and the like, comprising an air passage, a producer gas passage, a relatively large heating chamber, and a mixing and combustion chamber with which said air and gas passages communicate, said mixing and combustion chamber gradually increasing in cross section towards said heating chamber, substantially as described.

3. A producer gas combustion apparatus for glass furnaces and the like, comprising a relatively large heating chamber, a relatively long mixing and partial combustion passage gradually increasing in cross section towards said heating chamber and with which it connects near the bottom of said chamber, and fuel and air passages leading separately into said mixing passage at a distance from said heating chamber, substantially as described.

4. A producer gas combustion apparatus for glass furnaces and the like, comprising a heating chamber, a mixing and partial combustion chamber connecting with said heating chamber, a fuel supply passage of small area for feeding producer gas at high velocity into said mixing chamber, and separate air supply means for mixing air with said gas at a distance from said heating chamber, substantially as described.

5. A producer gas combustion apparatus for glass furnaces and the like, comprising a heating chamber, a mixing and partial combustion passage leading into the lower part of said heating chamber from a point a substantial distance below the said lead.

ing in point, and separate air and producer gas supply means leading into said mixing passage, substantially as described.

6. A producer gas combustion apparatus for glass furnaces and the like, comprising a heating chamber, a mixing and partial combustion passage leading into the lower part of said heating chamber from a point a substantial distance below the said leading in point, the said passage then directing its contents downwardly towards the bottom of said heating chamber, and air and producer gas supply means leading into said passage at a distance from said heating chamber, substantially as described.

7. A producer gas combustion apparatus for glass furnaces and the like, comprising a producer gas supply means having a narrow gas outlet subjected to full gas pressure and a clean-out chamber adjacent said outlet, independent air supply means surrounding said gas outlet, and a mixing and partial combustion chamber leading from the point of air supply to the outlet of said chamber and gradually increasing in cross section, substantially as described.

8. A producer gas combustion apparatus for glass furnaces and the like, comprising a thin narrow producer gas supply outlet subjected to full gas pressure, a mixing and partial combustion chamber having an outwardly flared end adjacent said gas outlet and freely communicating with the atmosphere, said chamber gradually increasing in cross section in a direction opposite to the flared end, and a heating chamber into which said chamber leads, substantially as described.

9. A producer gas combustion apparatus for glass furnaces and the like, comprising a heating chamber, a producer gas supply means, a separate mixing and partial com-

bustion chamber adjacent the delivery end of said gas supply means and separated therefrom sufficiently to allow a free supply of air, said chamber gradually increasing in cross section and communicating with said heating chamber, substantially as described.

10. A producer gas combustion apparatus for glass furnaces and the like, comprising a raw producer gas supply means, a gas port connecting directly with said means, a valve for closing said port connection, a thin narrow gas outlet from one end of said port, a clean-out chamber underneath said outlet, a mixing chamber adjacent said gas outlet and having a flared end towards said outlet and separate therefrom to allow free supply of air, said chamber gradually increasing in cross section away from said flared end, and a heating chamber into which said chamber opens, substantially as described.

11. A producer gas combustion apparatus for glass furnaces and the like, comprising a raw producer gas supply means, a gas port connecting directly with said means, a valve for closing said port connection, a thin narrow gas outlet from one end of said port, a clean-out chamber underneath said outlet, a mixing chamber adjacent said gas outlet and having a flared end towards said outlet and separate therefrom to allow free supply of air, said chamber gradually increasing in cross section away from said flared end, and a heating chamber into which said chamber opens by a downwardly directed portion and at a point a substantial distance above said flared end, substantially as described.

In testimony whereof, I have hereunto set my hand.

HENRY F. CLARK.
